UNITED STATES PATENT OFFICE.

RICHARD DAVID METCALFE AND JAMES CROXON METCALFE, OF ROMILEY, ENGLAND.

INJECTOR.

1,076,220.

Specification of Letters Patent.

Patented Oct. 21, 1913.

Application filed June 26, 1913. Serial No. 775,941.

To all whom it may concern:

Be it known that we, RICHARD DAVID METCALFE and JAMES CROXON METCALFE, subjects of the King of Great Britain and Ireland, residing at Injector Works, Romiley, in the county of Chester, England, have invented certain new and useful Improvements in Injectors, of which the following is a specification.

10 This invention relates to injectors and has for its object to provide an improved and simplified combination and arrangement of parts for adapting an injector to work efficiently and automatically with both 15 hot and cold feed water and high pressure steam.

Heretofore various arrangements of injectors have been proposed for regulating or controlling the overflow from the combining 20 nozzle when the injector is starting and when it is working normally. For example, in the specification of our United States Patent No. 905206, we proposed to divide the overflow chamber into two compartments 25 and to provide upon the one compartment a free or unloaded overflow valve while the other compartment has a valve thereon loaded by the pressure in the injector delivery chamber. This arrangement, while quite 30 satisfactory in operation, is relatively expensive to construct.

According to our present invention, we provide a simple combination of parts which is economical to make and which is efficient 35 in action. The said combination comprises the provision in an injector having a free non-return flap arrangement on the combining nozzle and an overflow passage or channel controlled by the pressure in the delivery 40 chamber, of a spring adapted to oppose the pressure in the delivery chamber and so compressed that when the injector is starting, the overflow valve can be readily opened while said valve is held closed during normal 45 working.

Referring to the accompanying sheet of explanatory drawings: Figure 1 is a sectional plan view, Fig. 2 a sectional elevation and Fig. 3 a cross section on the line A—B 50 of Fig. 1 showing an injector constructed in accordance with our invention.

The same reference letters in the different views indicate the same parts.

The injector comprises a steam nozzle *a*, 55 a water inlet connection *b*, a combining nozzle *c* in which the steam and water unite, and a delivery nozzle *d* in which the kinetic energy of the jet is converted into pressure energy. The water from said nozzle passes through the delivery chamber *e* to the outlet *f*.

When the injector is starting, steam entering by the nozzle *a* issues into the nozzle *c* and by an ejector action draws water in from the connection *b*. It will be readily understood that no delivery can take place from the injector until the steam jet is condensed by the feed water from *c* which is then given a high velocity. It is therefore necessary to provide that until the jet in the combining nozzle has sufficient velocity and the proper density to effect delivery against the pressure in the boiler or vessel being fed, there shall be a free escape from the combining nozzle to the overflow passage *g*. But a further condition also has to be satisfied in regard to the overflow from the combining nozzle, for it is found that if the steam pressure be high and the initial feed water temperature also high, there may be a pressure considerably above atmospheric in the overflow chamber when the injector is working normally. A free escape of overflow such as is required when the injector is starting would not therefore be of service when the injector is working normally.

To allow of the free escape from the combining nozzle, we provide not only a gap *h* between the combining and delivery nozzles but also a flap *i*. The pressure at the gap *h* is during normal working of the injector always greater than at the point where the flap *i* is situated, so that by closing the overflow chamber *f* we can cause the said excess of pressure to hold the flap closed, when the combining nozzle presents an unbroken channel for the flow of the steam and water during mixing.

As already explained, the overflow from the combining nozzle should not be restricted until the jet is able to deliver into the vessel being fed. It is, however, found in practice that even at starting when no delivery is taking place from the injector (but steam only is issuing into the combining nozzle) a considerable pressure may exist in the delivery chamber, such pressure gradually rising as normal conditions become established until it is able to force open the back pressure valve between the injector and the

boiler being fed. It will be understood, therefore, that merely to load the overflow valve *k* by the pressure in the chamber *e* would cause a throttling of the overflow 5 from the combining nozzle at starting and therefore impair the lifting automatic restarting powers of the appliance. To overcome this objection (which in our previous patent was obviated by the division of the 10 overflow chamber into two compartments, one of which had a free or unloaded valve thereon) we provide a spring *m* acting on the lever *n* to oppose the pressure in the delivery chamber acting on the plunger *o*. 15 The lever *n* loads the valve *k* through the medium of the strut *p*.

The strength of the spring *m* must be sufficient to overcome the pressure which is created at starting or restarting in the delivery chamber as before explained and the inertia and friction of the plunger *o*, lever *n* and strut *p* so that no load is placed upon the overflow valve *k* until normal working conditions are established. When working 20 with low pressure steam, however, the spring pressure may be greater than the delivery pressure but under such conditions the overflow pressure will during normal working be less than atmospheric. We therefore 25 make the overflow valve *k* entirely independent of the automatic loading means and such that it always tends to rest upon its seat and so seal the overflow passage. It will be seen that the valve *k* is a flap or 30 hanging valve pivoted about the pin *k'*.

The operation of the injector with hot feed water and high pressure steam is as follows: At starting the reduced pressure in the delivery chamber *e* is effectually resisted 35 by the spring *m* and the overflow valve *k* is free to open. The steam issuing into the combining nozzle therefore forces open the flap *i* and issues into the overflow chamber *j* and thence through the overflow pipe *q* past 40 the valve *k*. When, however, the injector commences to work normally, the pressure in the delivery chamber rises above the pressure in the overflow chamber together with 45 the pressure exerted by the spring *m* and so 50 loads the valve *k* and seals the overflow chamber, thus preventing the overflow which would otherwise take place due to the pressure in the overflow chamber being greater than atmospheric. Immediately the valve 55 closes, the pressure at the gap *h* being greater than at the flap *i*, due to the higher tempera-

ture of the jet at that point, acts upon and closes the flap so giving an unbroken nozzle for the flow of the jet during mixing.

Our improved injector is economical to 60 make and is efficient in action.

Having now described our invention what we claim as new and desire to secure by Letters Patent is:—

1. In injectors, in combination, a steam 65 nozzle, a combining nozzle, a delivery nozzle, an overflow chamber, a delivery chamber, a water inlet, an overflow gap between the combining and delivery nozzles, freely opening and closing overflow means upon the 70 combining nozzle; an overflow valve, means loading said overflow valve by the pressure in the injector delivery chamber, and means partly neutralizing said pressure, as set forth. 75

2. In injectors, in combination, a steam nozzle, a combining nozzle, a delivery nozzle, an overflow chamber, a delivery chamber, a water inlet, an overflow gap between the combining and delivery nozzles, freely opening and closing overflow means upon the combining nozzle, a free overflow valve upon the overflow chamber, a plunger loaded by the pressure in the delivery chamber, a lever and a rod conveying the load upon said 85 plunger to said overflow valve and means preventing the loading of said overflow valve until the plunger load exceeds a predetermined amount, as set forth. 80

3. In injectors, in combination, a steam 90 nozzle, a combining nozzle, a delivery nozzle, an overflow chamber, a delivery chamber, a water inlet, an overflow gap between the combining and delivery nozzles, freely opening and closing overflow means upon the combining nozzle, a free overflow valve upon the overflow chamber, a plunger loaded by the pressure in the delivery chamber, a lever and a rod conveying the load upon 95 said plunger to said overflow valve, and a spring preventing the loading of said overflow valve until the injector delivery pressure overcomes the spring resistance, as set forth. 100

In testimony whereof we have signed our 105 names to this specification in the presence of two subscribing witnesses.
